UNITED STATES PATENT OFFICE

HENRI CHIREIX, OF PARIS, FRANCE

ELECTRICAL SIGNALING

Application filed March 23, 1925, Serial No. 17,624, and in France June 17, 1924.

My invention relates to electrical signaling and more particularly to receiving systems for the reception of signal waves.

An object of my invention is the provision of simplified apparatus having the following advantages when employed with receiving systems designed for the reception of comparatively high frequency waves:

1. Effecting the reception of comparatively low frequency waves as well as high frequency waves by said high frequency receiving system.
2. Effecting reception over a very great range of signal frequencies.
3. Effecting regenerative amplification of radio telephony waves without distortion even when the frequency is low.
4. Minimizing the effects of disturbing oscillations by the use of an aperiodic antenna or a Beverage antenna.

Other objects and advantages of my invention will be apparent from the following description taken in connection with the accompanying drawings in which:

25 Fig. 1 is a schematic diagram of a modification of my invention.

Fig. 2 is a schematic diagram of another modification disclosing alternative features.

Referring to Fig. 1, the receiving system 30 comprises two parts, A and B, the part A containing the necessary apparatus designed for the normal reception, detection and amplification of comparatively high frequency waves; while the part B comprises the necessary apparatus for use together with the receiver A for readily effecting the reception, amplification and detection of comparatively low frequency waves.

The receiver A comprises a locally tuned 40 circuit 1 which ordinarily is the antenna circuit, a radio frequency triode amplifier 2, a triode detector 3, two audio frequency triode amplifiers 4 and 5 and a signal responsive device 6.

45 The local circuit 1 comprises an inductance coil 7 shunted by variable condenser 8 for tuning the said local circuit to the incoming high frequency signal waves. The grid and filament of amplifying triode 2 are connected across the local circuit, while the plate fila-

ment circuit is coupled to the grid filament circuit of detecting triode 3 by means of transformer 9. The plate filament circuit of detecting triode 3 is inductively coupled to the grid filament circuit of amplifying triode 55 2 by means of the coils 7 and 10. It is to be noted that this feed-back occurs at high radio frequency.

The plate filament circuit of detecting triode 3 is inductively coupled to the input of the audio frequency amplifier triode 4 by means of transformer 11. The output circuit of triode 4 is in turn inductively coupled to the input circuit of audio frequency amplifier triode 5 by means of transformer 12. 60 65 A signal responsive device 6 is connected in the output circuit of amplifying triode 5. The usual common filament battery and plate battery for supplying the various filaments and plate circuits are provided as shown. 70

The part B comprises a local circuit 13, a radio frequency amplifying triode 14 and a local generator of auxiliary waves 15. The local circuit 13 comprises an inductance coil 16 and a variable condenser 17 connected in 75 shunt therewith for tuning the local circuit to the comparatively low frequency waves.

The input of amplifying triode 14 is connected across the local circuit 13, while the output is connected across the local circuit 1. 80 The output circuit of amplifying triode 14 is also inductively coupled to a local generator of auxiliary waves 15 by means of the transformer 18. As the local oscillator with its associated circuits is well known in the 85 art, a detailed description thereof is unnecessary.

An antenna 19, preferably of the aperiodic or Beverage types, is connected to one terminal of the local circuit 13, the other terminal 90 being connected to the ground.

It is customary to call the combination of two adjacent radio frequencies which differ by an audio frequency, beating, and to call the combination of a radio frequency and an 95 audio frequency, which differ by a radio frequency, modulation. My invention involves the combination of a radio frequency with another radio frequency, resulting in the production of still other radio frequencies. The 100

magnitude of these frequencies are such that the two combined frequencies differ by a frequency which is nearer the larger than the smaller, so that the phenomenon, considered in terms of an audio frequency, is more like modulation than beating. I shall therefore throughout this specification use the term modulation in a broad sense, meaning the combination of frequencies so different that their difference is a frequency closer to the greater than to the smaller of the two original frequencies. I shall explain my invention by a specific example as follows.

Suppose that the receiver A is arranged to respond to frequencies in the neighborhood of 500,000 cycles, while it is desired to receive a comparatively low frequency, say 50,000 cycles. In this case the local circuit 13 is tuned to 50,000 cycles by means of the variable condenser 17 while the local oscillator 15 is arranged to generate waves at a frequency of 450,000 cycles. These auxiliary waves are modulated by low radio frequency waves, and the resulting modulated wave will have components or side frequencies of 500,000 cycles and 400,000 cycles.

The local circuit 1 is tuned to one of the side frequencies, in this case the 500,000 cycle frequency, by means of the variable condenser 8. The side frequency component, which represents the effect of the low radio frequency, is also modulated in substantially the same manner as the transmitted signal wave. Hence, in telephone work, the side frequencies are really side bands. The modulated high frequency wave is fed to the receiver A where it is suitably detected and amplified. By obtaining a proper frequency in the local oscillator, the receiver A may be efficiently applied to any frequency lower than its normal range. This arrangement permits the regenerative amplification without distortion because feed-back is not attempted at the low radio frequency.

Another modification fitted for greater received radio frequency amplification is represented in Fig 2. Referring to that figure, the receiving system comprises an antenna circuit having preferably an aperiodic antenna 20 and a tuning coil 21 both connected in series and grounded at G as shown. A resistance 22 is connected across the tuning coil 21, as shown, and it helps insure aperiodicity.

The input of amplifying triode 23 is connected across the resistance 22 while the output of amplifying triode 23 is connected to the input of amplifying triode 24 by means of a well known resistance coupling device comprising resistances 25 and 26 and condenser 27. A condenser 28 is connected across the resistance 25 to by-pass high frequency energy collected by the antenna, and so prevent the passage of undesirable high frequency waves through the amplifying

triode 24. The received frequency is relatively low, and as opposed to this low frequency energy, the impedance of the condenser 28 is great. The output of amplifying triode 24 is connected to the input of amplifying triode 29 by a well known resistance coupling device comprising resistances 30 and 31 and condenser 32 connected as shown. A resonant shunt, comprising an inductance coil 33 and condenser 34 connected in series therewith, is connected across the terminals of resistance 31.

The output of amplifying triode 29 is connected to the input of amplifying triode 35 by means of a well known resistance coupling device comprising resistances 36 and 37 and a condenser 38 connected as shown. A resonant shunt, comprising inductance coil 39 and condenser 40 connected in series therewith, is connected across the terminals of resistance 37.

The output circuit of amplifying triode 35 comprises a coil 41 and an inductance coil 42 connected in series as shown. A variable condenser 43 is connected across the terminals of inductance coil 42 while a local generator of auxiliary waves is inductively coupled to the output circuit of amplifying triode 35 by means of the coils 41 and 44. A coupling condenser 45 is provided for coupling the high resistance 46 to the above described system.

As a specific example of the operation of this system, assume that signal waves of a frequency of 20,000 cycles are to be received, and that a frequency of 220,000 cycles is desired. The local generator is then adjusted to produce auxiliary waves at a frequency of say 200,000 cycles. These waves are modulated by the signal waves, and there are produced side bands with mean frequencies of 180,000 or 220,000 cycles. The parallel resonant circuit 42, 43 is tuned to one of these frequencies, say 220,000, and is excited by that component. The output is taken from opposite terminals of the resistance 46, which is connected across the resonant circuit 42, 43 and its source of potential. The condenser 45 stops the steady component but passes the alternating component of the plate potential.

The series resonant shunt, comprising inductance coil 33 and condenser 34, is preferably tuned to 220,000 cycles; while the series resonant shunt, comprising inductance coil 39 and condenser 40, is preferably tuned to 420,000 cycles. These resonant shunts will therefore prevent the production of the desired side frequency from certain interfering waves and will also attenuate the effects of waves having a frequency equal to the side frequency. Thus, if some near station transmits at a frequency of 220,000 cycles, its influence would seriously affect the parallel resonant circuit 42, 43, but the series resonant circuit 33, 34 short circuits this energy before

it can reach the output circuit. A short wave transmitter tuned to a frequency of 420,000 is also found troublesome, probably because it coacts with the local oscillator to affect the circuit 42, 43 by the difference of their frequencies, and such 420,000 cycle energy is short circuited by the series resonant circuit 39, 40. Furthermore, the spread of high frequency energy and its harmonics from the local oscillator thru the preceding amplifying tubes by means of the natural capacitive coupling within the tubes is effectively reduced by the resonant and capacitive shunts employed.

To state the frequency relations more generally, the resonant shunt comprising the inductance coil 33 and condenser 34 is tuned to a frequency equal to the mean signal frequency to be received plus or minus the frequency of the auxiliary waves, that is, it is tuned to the same frequency as the receiver; while the resonant shunt comprising inductance coil 39 and condenser 40 is tuned to a frequency equal to the mean signal frequency to be received plus or minus twice the auxiliary frequency, in other words, to twice the frequency of the received energy. The local circuit comprising the inductance coil 42 and the variable condenser 43 is tuned to the desired side frequency. The capacity 28, and the series resonant circuits 33, 34 and 39, 40 constitute a filter which rids the tube 35 of a great many interfering and parasitic oscillations.

Disturbing influences due to static and interfering signal waves are very largely eliminated owing to the fact that none of the elements constituting this system are tuned to the signal frequency or even to a frequency in the neighborhood of signal frequencies. It is to be understood that any kind of receiving apparatus arranged for short wave reception and detection may be connected across the resistance 46, an example being the receiver A in Fig. 1.

While I have shown and described various embodiments of my invention, I do not limit myself to the same but may employ such other modifications as come within the spirit and scope of my invention.

I claim:

1. The method of changing modulated low radio frequency energy to modulated high radio frequency energy which consists in collecting modulated low radio frequency energy, generating unmodulated high radio frequency energy, using the modulated low radio frequency energy to modulate said unmodulated high radio frequency energy and separating from the resulting energy an energy band the main frequency of which is a side frequency of said modulated high radio frequency energy.

2. The method of receiving energy of relatively low radio frequency with a receiver

adapted for the reception of energy of relatively high radio frequency which consists in collecting modulated signal energy of a low radio frequency, locally generating unmodulated energy of a relatively high radio frequency, modulating the latter energy with the collected energy, and utilizing for reception one of the said frequency components of the locally modulated high radio frequency energy.

3. Apparatus for the reception of relatively low radio frequency energy comprising an antenna, a regenerative receiver tuned to a relatively high radio frequency, coupling means including an oscillator tuned to oscillate at a frequency which is the sum or difference of the low and high radio frequencies and means to prevent energy at relatively high frequency from passing from the antenna through the coupling means.

4. Apparatus for the reception of energy at low radio frequency f comprising an antenna, a receiver tuned to a high radio frequency F , and coupling means including a low radio frequency amplifier connected to the antenna and an oscillator tuned to generate an unmodulated wave of high radio frequency ($F \pm f$) connected to the output of said amplifier.

5. In combination, an oscillator adapted to produce unmodulated energy, means for collecting signal energy, means coupling the collecting means to the oscillator, so that the signal energy modulates the energy generated by the oscillator, a resonant circuit tuned to a side frequency of the modulated oscillator energy, and detecting means coupled to the tuned circuit.

6. In combination, an oscillator adapted to produce unmodulated energy at a high radio frequency, an aperiodic antenna for collecting modulated low radio frequency energy, radio frequency amplifying means coupled thereto, means coupling said amplifying means to said oscillator so that the energy of the latter is modulated by the amplified collected energy, a resonant circuit tuned to a side frequency of the modulated radio frequency energy, and detecting means coupled to the tuned circuit.

7. In combination, an aperiodic antenna, a resistance coupled radio frequency amplifier coupled to an oscillator the energy of which is modulated by the received amplified energy, a resonant circuit tuned to a side frequency of the modulated energy, detecting means coupled to the resonant circuit, and a filter system adjusted to prevent received energy having the frequency to which the resonant circuit is tuned from affecting said resonant circuit.

8. The method of reception which consists in collecting modulated signal energy at a low frequency, locally generating unmodulated energy at a relatively high radio frequency.

quency, modulating said latter energy with said modulated signal energy, and utilizing one of the side frequency components of the modulated high radio frequency energy.

5 9. A method of receiving modulated low radio frequency energy with a high radio frequency receiver which consists in collecting said low radio frequency energy, locally generating unmodulated energy at a high
10 radio frequency within the range of the said receiver, modulating said latter energy with said collected energy, and detecting the modulated high radio frequency energy.

10. In a method, as defined in claim 9, the
15 step of detecting only the upper side frequency of the modulated high radio frequency energy.

11. A method of reception which consists in collecting modulated signal energy at a low radio frequency, locally generating unmodulated energy at a higher radio frequency, modulating said higher radio frequency energy with said modulated signal energy, detecting the modulated higher radio frequency energy, and suppressing all collected energy which has a frequency equal to said modulated higher radio frequency energy.
